(57) **CLAIM**

The ornamental design for a USB type-C receptacle, as shown and described.

DESCRIPTION

FIG. 1 is an isometric view of a USB type-C receptacle showing our new design;

FIG. 2 is another isometric view of the USB type-C receptacle of FIG. 1;

FIG. 3 is a front elevational view of the USB type-C receptacle of FIG. 1;

FIG. 4 is a right side elevational view of the USB type-C receptacle of FIG. 1;

FIG. 5 is a rear elevational view of the USB type-C receptacle of FIG. 1;

FIG. 6 is a left side elevational view of the USB type-C receptacle of FIG. 1;

FIG. 7 is a top plan view of the USB type-C receptacle of FIG. 1; and,

FIG. 8 is a bottom plan view of the USB type-C receptacle of FIG. 1.

The broken lines represent portions of the USB type-C receptacle that form no part of the claimed design.
